BOTTLE CARRIER

Marcel L. Everhart, Washington, D. C., assignor
of one-half to Daniel Holland, Washington,
D. C.

Application March 5, 1947, Serial No. 732,564

4 Claims. (Cl. 294—87.22)

1

This invention relates to a bottle handling device, and it relates more particularly to a device for picking up a group of bottles so that they may be easily transferred to another position and deposited at the second position while maintaining the bottles of the group in their original alignment and relative spacing.

In the beverage industry, and particularly in the soft drink industry, the beverage bottles are usually handled in cases containing twenty-four bottles. The bottles are equally spaced in the case in six transverse rows of four bottles in each row. Since the bottles in these industries are re-used for delivery of the beverage to the consumer, it is, of course, necessary that they be handled from time to time such as in the bottle washing and sterilizing operation. All beverage bottling plants have large bottle washing machines through which the bottles are carried on conveyers. When the empty bottles are returned to the bottling plant, they are deposited upon the conveyer of the bottle washing machine, and this operation has heretofore been performed manually by an attendant who transfers two bottles at a time with each hand from the case to the conveyer of the bottle washing machine.

It is apparent, therefore, that the present practice is a laborious one, which requires a single attendant to work at top speed; or as an alternative two attendants must be employed, thereby increasing the cost of the operation.

It is, therefore, an object of this invention to provide a bottle transfer device by the use of which a single attendant is enabled to transfer the bottles from the incoming cases to some other position such as the conveyer of a bottle washing machine.

In its specific embodiment the invention contemplates a device by means of which the attendant may transfer twelve bottles in a single easy operation. However, the number of bottles for which the device is designed is not of particular importance so long as it is adapted to handle a plurality of bottles at each operation.

Other objects and advantages of the invention will become clear as the specific description thereof proceeds with reference to the accompanying drawing in which:

Fig. 1 is a perspective view of the bottle transfer device;

Fig. 2 is a plan view of the device;

Fig. 3 is a longitudinal sectional view;

Fig. 4 is a transverse sectional view;

2

Fig. 5 is a detail view showing one form of bottle gripping blades; and

Fig. 6 is a detail view of a different type of bottle gripping blades.

In substance the device consists of a rectangular frame 10, which is composed of side members 12 and 14 and end members 16 and 18. The side members 12 and 14 are of such length as to adapt the device to the width of the conventional bottle case. The length of the end members 16 and 18 is fixed by the predetermined capacity of the device. Thus, if it is designed to handle a whole case of bottles at a single operation, the end members 16 and 18 will correspond generally in length to the length of a conventional bottle case. In the exemplary embodiment of the invention shown herein, the length of the end members 16 and 18 is approximately half the length of the conventional bottle case. Thus, the embodiment of the device herein is designed to handle three transverse rows of bottles at a single operation.

The end walls 16 and 18 carry four spaced parallel rods 20, 22, 24 and 26. These rods are suitably fixed to the end walls 16 and 18, and, herein, such fixing structure consists of sockets in the end walls for receiving the respective ends of the rods 20 through 26.

Each of the transverse parallel rods 20 through 26 carries a plurality of bottle gripping blades 28, constituting a set. In the specific disclosure herein there is provided a separate gripping blade for each bottle in the transverse row. In other words, there are four separate gripping blades, supported on each of the parallel rods, each blade being separated from the adjacent one by a spacing washer. Furthermore, the two inwardly disposed rods carry oppositely extending gripping blades, while the two outer rods carry only a single set of inwardly extending gripping blades. As a consequence of the structure there is provided a pair of confronting gripping blades for each bottle neck within the group of bottles for which the mechanism is designed.

Each gripping blade is biased downwardly by means of spring arms 30, which bear against the upper surface of the respective blades. In the instant disclosure the spring arms 30 are the end extensions of a coil spring 32 surrounding the gripping blade supporting rod. It will be clear, therefore, that the gripping blades 28 are urged downwardly, which is the normal bottle gripping position. On the other hand, they are free to swing upwardly into a bottle admitting position when the device is in operation. It is contem-

plated that the bottles be engaged about their necks by the gripping blades 28 merely by positioning the device over a group of aligned bottles and applying sufficient pressure against the crowns of the bottles to force the gripping blades into open or bottle receiving position. Upon release of the downward pressure the gripping blades will engage the neck of the associated bottles and support them for transport to a second position.

The mechanism includes means for quick and easy release of the bottles, and herein that mechanism consists of a pair of end supports 34 and 36. These supports are positioned adjacent the inner face of the end members 16 and 18, respectively. Carried by the end supports 34 and 36 are a plurality of rods 38, which underlie the bottle gripping blades 28. By reference to Fig. 4 it will be seen that the gripping blade support rods 20, 22, 24 and 26 extend through slots 40 formed in the end supports 34 and 36. These slots permit the end supports 34 and 36 together with their attached rods 38 to move relative to the frame 10.

The underlying rods 38 limit the downward movement of the gripping blades 28, but their principal function is to effect the release of bottles held in the mechanism, and such release is easily brought about by shifting the position of the end supports 34 and 36 with relation to the main frame 10. Thus, when an operator grips the end walls of the frame 10 and depresses it with reference to the end supports 34 and 36, the underlying rods 38 will effectively move the gripping blades upwardly against the tension of the spring arms 30. Since the distance between the ends of the confronting gripping blades is increased by this manipulation, the bottles are released, and they may thereby be deposited in their second position without disturbing the original alignment thereof.

The conventional bottle which is used for beverages such as the various carbonated soft drinks or beer is of the crowned type, i. e., the mouth of the bottle is formed with a crown in the nature of an annular rim adapted to receive a crimped closure cap. Below the crown is a slightly bulbous formation in an annular direction, which results in a second protuberance. In Figs. 5 and 6 is illustrated the neck portion of a conventional beverage bottle, and in these figures the crown portion 42 defines the mouth or pouring opening of the bottle. Immediately below the crown 42 is an annular groove 44, and from that point the neck of the bottle flares outwardly as at 46, thereby defining a second annular groove 48 immediately below.

In the simplest form of the invention the bottle gripping blades 28 may be formed with bevelled bottle engaging edges 50 which are adapted to engage either the annular depression 44 immediately below the crown of the bottle or the annular depression 48 which is located slightly lower on the neck of the bottle.

The bottle gripping blades may be modified as suggested in Fig. 6 of the drawing wherein the blades 52 are provided with an edge configuration adapted to embrace each bottle neck at two points. Thus, the blades are provided with an outer angular edge 54 and an inwardly spaced angular edge 56 so that the outer edge 54 may engage the annular groove 44 immediately below the lip of the bottle while the inwardly positioned edge 56 may engage the annular depression 48, 75

which is located a slight distance downwardly on the neck of the bottle.

From the foregoing it will appear that the device is of extremely simple construction and that its operation requires no skill whatever. The specific mode of use has been developed as this specification has proceeded, and a recapitulation thereof does not seem required.

Having described the invention in one operative form, I claim the following:

1. A bottle carrier, comprising a frame having side members and end members, parallel rods extending between said end members, a plurality of bottle gripping blades constituting a set mounted on each of said rods for angular movement thereabout, the blades of each set being arranged on said rods in transverse alignment with blades of the other sets, thereby presenting spaced confronting free edges, resilient means urging said blades angularly about said rods, a supporting rod underlying the blades of each set thereby limiting the angular movement of said blades under the influence of said resilient means, and means for simultaneously moving said supporting rods against said blades in opposition to the force of said resilient means.

2. A bottle carrier, comprising a frame having side members and end members, parallel rods extending between said end members, a plurality of bottle gripping blades constituting a set mounted on each of said rods for angular movement thereabout, the blades of each set being arranged on said rods in transverse alignment with blades of the other sets, thereby presenting spaced confronting free edges, a spring associated with each blade for independently urging said blades angularly about said rods, an actuating member movably mounted with respect to each of said end members, supporting rods having their ends supported in said actuating members and underlying the blades of each set thereby limiting the angular movement of said blades under the influence of said resilient means, and means for moving said actuating members to simultaneously press said rods against said blades in opposition to the force of said springs.

3. A bottle carrier, comprising a frame having side members and end members, parallel rods extending between said members, a plurality of bottle gripping blades constituting a set mounted on each of said rods for angular movement thereabout, the blades of each set being arranged on said rods in transverse alignment with blades of the other sets, thereby presenting spaced confronting free edges, resilient means urging said blades angularly about said rods, an end support mounted against the inner face of each of said end members, blade supporting rods extending longitudinally along the under side of each set of blades and having their ends mounted in said end supports, and slots in said end supports straddling said parallel rods whereby said end supports and said supporting rods may be moved relative to said frame for angularly rotating said blades against the force of said resilient means.

4. A bottle carrier, comprising a frame having side members and end members, parallel rods extending between said members, a plurality of bottle gripping blades constituting a set mounted on each of said rods for angular movement thereabout, the blades of each set being arranged on said rods in transverse alignment with blades of the other sets, thereby presenting spaced confronting free edges, a spring associated with each blade for independently urging said blade angu-

larly about said rods, an end support mounted against the inner face of each of said end members, blade supporting rods extending longitudinally along the under side of each set of blades and having their ends mounted in said end supports, and slots in said end supports straddling said parallel rods whereby said end supports and said supporting rods may be moved relative to said frame for angularly rotating said blades against the force of said springs.
